UNITED STATES PATENT OFFICE.

GEORG ENGELHARDT, OF CASSEL, AND CARL FRIEDRICH FÖLSCH, OF WERNIGEROODE-ON-THE-HARZ, GERMANY.

MEASURING DEVICE FOR SHOE-LASTS AND FOOT-COVERINGS.

No. 806,531.

Specification of Letters Patent.

Patented Dec. 5, 1905.

Application filed February 18, 1905. Serial No. 246,259.

To all whom it may concern:

Be it known that we, GEORG ENGELHARDT, manufacturer, and a resident of Cassel, and CARL FRIEDRICH FÖLSCH, manufacturer, and 5 a resident of Wernigerode-on-the-Harz, Kingdom of Prussia, Germany, subjects of the German Emperor, have invented a new and Improved Measuring Device for Shoe-Lasts and Foot-Coverings, of which the following 10 is a full, clear, and exact description.

The object of the invention is to provide a new and improved measuring device for shoe-lasts and foot-coverings arranged to permit of obtaining the proper position of the toe portion 15 relative to the main or heel portion of the wearer's foot.

The invention consists of novel features and parts and combinations of the same, as will be more fully described hereinafter and then 20 pointed out in the claims.

Practical embodiments of the invention are represented in the accompanying drawings, forming a part of this specification, in which similar characters of reference indicate cor- 25 responding parts in all the views.

Figure 1 is a face view of the improvement in the form of a measuring-chart for determining the angular position of the toe portion relative to the main foot portion. Fig. 2 is a 30 plan view of the improvement in the form of a measuring apparatus. Fig. 3 is a cross-section of the same on the line 3 3 of Fig. 2, and Fig. 4 is a longitudinal sectional elevation of the same on the line 4 4 of Fig. 2.

The chart shown in Fig. 1 is provided with 35 a line *a b*, which forms a guide for the inner side of the foot, and at right angles to this line, at or near one end thereof and beyond the point *c*, is arranged a graduated line *d e*, 40 extending on both sides of the line *a b*. Both sides of the line *d e* have their graduation-points marked alike by consecutive numerals—as shown by the numerals “2” to “15”—and from the point *c* extend radial lines to the 45 points marked by the numerals on the graduated line *d e*. The chart is also provided with equidistant lines, marked on each side of the chart by a linear graduation indicating the length of the foot from the back of the heel 50 to the beginning of the big toe, the graduation being in linear-measurement units, such as centimeters. In using this chart the foot is placed on the chart, as indicated in Fig. 1, so that the inner side of the foot extends along

the line *a b*, and the back of the heel is placed 55 on the transverse line indicating the length of the foot from the back of the heel to the beginning of the big toe, for instance, as shown in Fig. 1, on the line 40. When the radial line extending from the point *c* to the graduated line *d e* is tangential to the big toe of the foot, this line indicates the angular position of the big toe to the main portion of the foot.

In practice the chart is preferably made of 65 a transparent material—such as celluloid, tracing-cloth, and the like—and in using the chart it may be of advantage for the shoemaker to first obtain an outline drawing on a piece of paper of the foot and then place the 70 same under the transparent chart, so as to permit the shoemaker to conveniently obtain the angular position of the toe portion relative to the main portion of the foot.

If a number of lasts for one series—say four 75 lasts—are used in the manufacture of shoes and the like, the last is selected which agrees the nearest in the angular position of the toe portion relative to the main foot portion to the one obtained by the use of the chart. 80

In the apparatus shown in Figs. 2, 3, and 4 a base 2 is employed, on which extends a raised strip forming the guide 1, on which is mounted to slide a slide 3, abutting against the back of the heel of the foot, the angular 85 position of the big toe of which is to be obtained relative to the main foot portion. On the top of the guide 1 are arranged two graduations “4” and “5,” of which the graduation “4” indicates the entire length of the foot in 90 unit measurements and the graduation “5” indicates in the same units the length of the foot from the back of the heel to the beginning of the big toe. A set-screw 7, which screws on the slide 3, serves to fasten the latter in position 95 on the corresponding graduation-mark of the graduation “4” or “5,” whichever is used at the time. In measuring the entire length of the foot use is made of a stop 8 at the upper end of the guide 1, from which the graduation “4” 100 is calculated, it being understood that the end of the big toe abuts against this stop 8 and the slide 3 is moved along the guide 1 until the forward edge of the slide abuts against the back of the heel. When this has been 105 done, the screw 7 is screwed up to fasten the slide 3 in place, the corresponding graduation marked on the graduation “4” indicating the

entire length of the foot, while the graduation on the scale 5 indicates approximately the length of the foot from the back of the heel to the beginning of the big toe. At this 5 point—that is, the beginning point of the big toe—is fulcrumed at 10 an arm 9 on each side of the guide 1, and each arm 9 when swung inward and outward is adapted to coincide with radial lines 11, extending from the axis 10 of the pivot 10 to a cross-line 20 20, the points of intersection between the lines 11 and 20 being indicated by consecutive numerals "12" leading from the side of the guide 1 outwardly, as plainly indicated in Fig. 2. When 15 the foot is placed on the base 2 so that the inner side of the foot rests against the corresponding side of the guide 1 and the arm 9 is swung against the side of the big toe, then the said arm indicates on the corresponding 20 numeral on the graduated line 20 20 the angular position of the toe portion relative to the main foot. It is understood that for the right foot the inner side thereof is abutted against the right side of the guide 1, while 25 the left foot is placed in position on the base 2, with the inner side of this foot abutting against the left-hand side of the guide 1. In either case, however, the foot is placed in such position on the base 2 that the beginning 30 point of the big toe coincides with the pivot 10 for the corresponding arm 9. The slide 3 is provided with integral sidewise-extending arms 13, on which are mounted to slide sidewise the offsets 14, adapted to be fastened by 35 clamping-bolts 22 to the arms 13, each clamping-bolt extending through an elongated slot 16, formed in the corresponding arm 13. By loosening the nut 15 for the bolt 22 the offset 14 can be moved inward or outward on the 40 arm 13, to bring the forward curved edge 18 of the offset 14 against the back of the heel of the foot after the same has been placed in position on the base 2 and the slide 3 has been moved up, as previously explained. The lower 45 end of the guide 1 is provided with a stop 19 to prevent the slide 3 from accidentally leaving the guide 1 when the screw 7 is loosened. In order to prevent accidental movement of the arm 9 after the same has 50 been adjusted, a spring 29 is held on each arm, but in contact with the face of the base 2, to allow swinging movement of the arm by the operator and to hold the arm in position after the same is adjusted. On the top of the base 55 2 is arranged a longitudinally-extending guide-rod 23, having a tape 24 to allow of measuring the width of the foot across the ball thereof. A numeral-table 26 is preferably arranged on the base 2 at one side thereof, and this numeral-table is provided with a graduation indicating a linear measurement corresponding to the graduation "4," and the graduation is headed with the width of the foot, as indicated by the numerals from "1" 60 to "8," such as obtained by the use of the

tape 24. The point of intersection being obtained by following the column indicating a certain width and the corresponding line for a certain length, the operator obtains a field for containing the number of the last for a 70 particular foot measure by the above-described device. The number obtained for the last is indicated for a whole series of lasts, which have a different relation relative to the angle of the toe portion with the main foot 75 portion.

As the manufactured shoes contain the number of the last, it is evident that by the use of the device above described the size of the foot, as well as width thereof, can be readily 80 obtained in using the table 26. In the same manner models or patterns for other foot-covings—such as stockings, rubber shoes, and the like—can be readily made, and the articles produced can be numbered according to the 85 measurements obtained.

We do not limit ourselves to the particular construction of the device above described and shown, as the same may be varied without deviating from the spirit of our invention.

Having thus described our invention, we claim as new and desire to secure by Letters Patent—

1. A measuring device comprising a base provided with a graduation, a guide on the 95 said base and at right angles to the said graduation, an arm swinging from the side face of the said guide, for determining the angular position of the big toe of the foot relative to the main portion and a heel-rest adjustable in 100 the direction of the length of the said guide.

2. A measuring device comprising a base provided with a graduation, a raised guide on the said base and at right angles to the said graduation, an arm swinging from the side 105 face of the said guide above the graduation of the base for determining the angular position of the big toe of the foot relative to the main portion, and a heel-rest adjustable in the direction of the length of the said guide and in 110 a direction transverse to the said guide.

3. A measuring device comprising a base provided with a graduation, a raised guide on the said base and at right angles to the said graduation, the face of the said guide having 115 graduations, an arm swinging from the side face of the said guide above the graduation of the base, for determining the angular position of the big toe of the foot relative to the main portion, and a heel-rest adjustable in the 120 direction of the length of the said guide and in a direction transverse to the said guide.

4. A measuring device comprising a base provided with a graduation, a measuring-guide on the said base and at right angles to the graduation, determining means intersecting the said graduation for determining the angular position of the big toe of the foot relative to the main portion, a heel-rest comprising a slide 125 movable along the measuring-guide, and slides 130

having curved edges and mounted to move laterally on the first-mentioned slide.

5. A measuring device comprising a base provided with a graduation, a measuring-guide on the said base, and at right angles to the graduation, determining means intersecting the said graduation for determining the angular position of the big toe of the foot relative to the main portion, a heel-rest comprising a slide 10 movable along the measuring-guide and having lateral arms, means for fastening the slide in position, and slides having curved edges and adjustable on the said lateral arms toward and from the said measuring-guide.

15. 6. A measuring device, comprising a base, provided with a graduation, a raised guide on the said base and at right angles to the said graduation, the face of the said guide being provided with graduations, an arm fulcrumed 20 on each side of said guide and indicating on the graduation of the base, and a heel-rest comprising a slide mounted on the guide and adjustable in the direction of the length of the guide, the said slide being provided with side 25 arms, and members adjustable on the side arms.

7. In a foot-measuring device, the combination with a base, of a straight graduated measuring-guide on the base for the inner side

of the foot, the base being provided with a 30 straight graduated line at right angles to the measuring-guide and extending on both sides thereof, the base being further provided with radial lines at each side of the measuring-guide, the said lines extending from a point on the 35 said measuring-guide and intersecting the said straight graduated line.

8. In a foot-measuring device, a base provided with a guide for the inner side of the foot, and with a graduated line at right angles to the guide, the base being further provided with radial lines extending from a point on the guide and intersecting the said graduated line.

In testimony whereof we have signed our 45 names to this specification in the presence of two subscribing witnesses.
